W. E. HUENEFELD

OIL BURNER FOR STOVES

Filed Aug. 4, 1922

UNITED STATES PATENT OFFICE.

WALTER E. HUENEFIELD, OF CINCINNATI, OHIO.

OIL BURNER FOR STOVES.

Application filed August 4, 1922. Serial No. 579,749.

To all whom it may concern:

Be it known that I, WALTER E. HUENEFIELD, a citizen of the United States, and a resident of Cincinnati, in the county of 5 Hamilton and State of Ohio, have invented certain new and useful Improvements in Oil Burners for Stoves; and I do hereby declare the following to be a full, clear, and exact description of the invention, such as 10 will enable others skilled in the art to which it appertains to make and use the same.

This invention relates to improvements in oil burners for stoves and more particularly to the wick operating means for the same,— 15 one object of the invention being to provide adjustable stop devices which shall be simple in construction and readily operable to regulate and control the limit to which it may be desired the wick shall be permitted to be 20 raised, and by means of which also the wick may be lowered sufficiently to cause a flame thereon to be extinguished.

With this and other objects in view, the invention consists in certain novel features 25 of construction and combinations of parts as hereinafter set forth and pointed out in the claims.

In the accompanying drawings, Figure 1 is a view in elevation showing the application 30 of my improvements to a burner. Figure 2 is a view partly in section and partly in elevation showing the wick-operating and stop devices. Figures 3 and 4 are end views 35 showing different positions which the wick operating devices may be caused to assume. Figure 5 is a view partly in elevation and partly in section on the line 5—5 of Figure 1, and Figure 6 is a view on the line 6—6 of Figure 2.

40 The burner 1 to which my improvements may be applied may comprise concentric outer and inner shells 2 and 3 which receive a wick 4 between them, said wick having secured thereto a perforated carrier 5 with 45 which the pinion for raising and lowering the wick meshes as is well known in burners of the type to which my improvements are applied.

The outer shell of the burner has secured 50 thereto a housing 6 which forms a chamber communicating with the wick compartment formed between the burner shells and with said chamber a connection 7 for an oil pipe communicates.

55 An inclined tube 8 is rigid at one end with the housing 6 and projects upwardly and lat-

erally from the burner,—said tube constituting a mounting for a wick operating spindle 9 provided at its lower end with a pinion 10 to mesh with the perforated wick carrier for effecting the raising and lowering of the wick. The tube 8 is provided near its free end with a disk 11 having a depressed central portion made rigid with said tube and at one point the said disk 11 is provided with a stop lug 12 which may be formed integral with and bent up from the metal of the disk.

The spindle 9 projects an appreciable distance beyond the free end of the tube 8 as indicated at 13 and has rigidly secured to its free end, a manually operable wheel 14 which is provided with an annular series of perforations 15.

Disposed between the disk 11 and the operating wheel 14 is a spring yoke or member 16, the respective members of which are made with perforations 17 for the accommodation of the portion 13 of the spindle 9 on which said spring yoke or member is freely mounted to turn. The lower member 18 of the spring yoke bears upon the disk 11 and is provided with a finger 19 to co-operate with the stop lug 12 on the disk, while the upper member 20 of the spring yoke bears against the under face of the operating wheel 14 and is provided with a tooth or lug 21 to enter one of the perforations in said wheel. The upper member 20 of the spring yoke is also provided with an arm 80 or finger piece 22 by means of which said upper member of the yoke may be depressed 90 to release the spring device from the operating wheel.

When the wick is being fed into the burner, the spring yoke will be released from the operating wheel so that the latter may be turned freely to effect the downward feeding of the wick until the upper end of the latter becomes flush with the upper ends of the burner shells. The spring yoke while still released from the operating wheel may then be turned to assume a position with the finger 19 diametrically opposite the stop lug 12 and then released to cause the tooth 85 or lug 21 to enter one of the perforations 15 in the operating wheel, thus locking said spring yoke and operating wheel together. By now turning the operating wheel a limited distance to the right the wick may be 100 raised sufficiently for starting purposes but it cannot be raised higher than will be per-

mitted by engagement of the finger 19 with the stop lug 12. If desired the spring yoke may first be locked to the operating wheel so that the finger 19 will be disposed a comparatively short distance from the stop lug 12 so that the limit of upward movement of the wick for starting purposes may be effected by turning the operating wheel until the finger 19 engages said stop 12. The 10 spring yoke may then be released from the operating wheel, turned to the left any desired distance and then permitted to again interlock with the operating wheel so that when the latter is subsequently turned to the 15 right the further raising of the wick will be limited by engagement of the finger 19 with the stop lug 12.

It will be seen with the use of my improvements, the spring yoke, which constitutes the adjustable portion of the stop devices, may be adjusted to any desired position relatively to the operating wheel so that the limit of height to which the wick may be raised may be predetermined and 25 controlled.

Slight changes might be made in the details of construction of my invention without departing from the spirit of the latter or limiting its scope and hence I do not wish to restrict myself to the precise details herein set forth.

Having fully described my invention what I claim as new and desire to secure by Letters Patent, is:

35 1. The combination with a burner, a tube secured thereto, and a disk rigid with said tube and provided with a stop, of a wick operating spindle passing through said tube and provided with a manually operable 40 member, and a yoke of spring metal disposed between said disk and manually operable member and adjustably cooperable

with the latter, one member of said yoke being cooperable with the stop on the disk to limit the height to which the wick may be 45 raised.

2. The combination with a burner and a tube secured thereto and provided with a disk having a stop, a wick operating spindle passing through said tube, an operating 50 wheel rigid with the free end of said spindle and having a plurality of perforations, a yoke of spring metal disposed between said disk and wheel and mounted to be turned or adjusted independently of the spindle, one 55 arm or member of said yoke being cooperable with the stop on said disk and the other member of said yoke having a finger piece, and a lug rigid with the last mentioned yoke member to enter any one of 60 the perforations in the operating wheel.

3. The combination with a burner and a tube secured thereto and provided at its free end with a disk having a fixed stop projecting therefrom, of a wick operating 65 spindle passing through said tube and projecting beyond the free end thereof, an operating wheel rigid with the free end of said spindle and provided with a plurality of perforations, a yoke of spring metal disposed between said disk and wheel and freely mounted on the projecting portion 70 of the spindle, one member of said yoke having a part to engage the stop on said disk and the other member of said yoke having a projection to enter any one of the perforations in the operating wheel.

In testimony whereof, I have signed this specification in the presence of two subscribing witnesses.

WALTER E. HUENEFELD.
